CLAIM

The ornamental design for a water timer, as shown and described.

DESCRIPTION

FIG. 1 is a front perspective view of a first embodiment of a water timer;

FIG. 2 is a rear perspective view of the water timer shown in FIG. 1;

FIG. 3 is a front view of the water timer shown in FIG. 1; FIG. 4 is a rear view of the water timer shown in FIG. 1; FIG. 5 is a left side view of the water timer shown in FIG. 1;

FIG. 6 is a right side view of the water timer shown in FIG. 1;

FIG. 7 is a top view of the water timer shown in FIG. 1; FIG. 8 is a bottom view of the water timer shown in FIG. 1; FIG. 9 is a front perspective view of a second embodiment of a water timer;

FIG. 10 is a rear perspective view of the water timer shown in FIG. 9;

FIG. 11 is a front view of the water timer shown in FIG. 9; FIG. 12 is a rear view of the water timer shown in FIG. 9; FIG. 13 is a left side view of the water timer shown in FIG. 9;

FIG. 14 is a right side view of the water timer shown in FIG. 9;

FIG. 15 is a top view of the water timer shown in FIG. 9; FIG. 16 is a bottom view of the water timer shown in FIG. 9;

FIG. 17 is a front perspective view of a third embodiment of a water timer;

FIG. 18 is a rear perspective view of the water timer shown in FIG. 17;

FIG. 19 is a front view of the water timer shown in FIG. 17; FIG. 20 is a rear view of the water timer shown in FIG. 17; FIG. 21 is a left side view of the water timer shown in FIG. 17;

FIG. 22 is a right side view of the water timer shown in FIG. 17;

FIG. 23 is a top view of the water timer shown in FIG. 17; and,

(Continued)

FIG. 24 is a bottom view of the water timer shown in FIG. 17;
 The broken line showing of portions of the water timer is for the purpose of illustrating unclaimed structure and forms no part of the claimed design.
